UNITED STATES PATENT OFFICE.

EDWARD M. STILES, OF MOUNT PLEASANT, IOWA, ASSIGNOR TO U. S. SLICING MACHINE COMPANY, OF LAPORTE, INDIANA, A CORPORATION OF INDIANA.

STACKER FOR SLICING-MACHINES.

1,290,402.

Specification of Letters Patent.

Patented Jan. 7, 1919.

Application filed June 13, 1917. Serial No. 174,435.

To all whom it may concern:

Be it known that I, EDWARD M. STILES, a citizen of the United States, residing at Mount Pleasant, in the county of Henry and 5 State of Iowa, have invented certain new and useful Improvements in Stackers for Slicing-Machines, of which the following is a specification.

This invention relates to mechanism for 10 stacking the slices of meat or other material, as they are cut by a slicing machine, and has for its object the provision of a device of the character named which shall be of improved construction and more efficient in 15 its operation than similar devices previously known.

The invention is exemplified in the combination and arrangement of parts shown 20 in the accompanying drawings and described in the following specification, and it is more particularly pointed out in the appended claims.

In the drawings, Figure 1 is a front elevation of a slicing machine having one embodiment of the present invention connected therewith; Fig. 2 is a top plan view of the machine shown in Fig. 1; Fig. 3 is a fragmentary detail; Fig. 4 is a vertical sectional view substantially on line 4—4 of Fig. 2; 30 Figs. 5, 6, 7 and 8 are detail views of the operating cam and associated parts for the stacker fly; Fig. 9 is a sectional elevation on line 9—9 of Fig. 4; Fig. 10 is a horizontal sectional view on line 10—10 of Fig. 9; Fig. 11 is a view similar to Fig. 10 but with 35 the stacker belt in discharging position; Fig. 12 shows a portion of the stacker belt and its relation to the slicing knife on a larger scale than that of Figs. 10 and 11; Fig. 13 is a detail of the support for the stack of slices.

In the operation of machines for slicing most materials, it is desirable to place the slices, as they are formed, in a pile or stack 45 on top of one another. It has been customary for the operator to grasp the slice as it is formed, in one hand, while he turns the machine with the other, and place the slices in stack formation. This, of course, 50 is an inconvenient method of operation and in many cases is unsanitary where the operator is not sufficiently careful with regard to the cleanliness of his hands. Moreover, during the slicing of meat and similar sub-

stance, this old mode of operation renders 55 the hands greasy so that they must be washed with soap before the operator may perform other tasks. It is, therefore, very desirable to provide a machine which shall perform the stacking operation mechanically.

In the drawings, the numeral 1 designates the base of a slicing machine which may be of well known and approved construction and which is provided with a 65 standard 2 carrying the usual form of disk knife 3 for cutting slices from a piece of material 4 carried on a reciprocating table 5. The table 5 is moved toward and away from the knife 3 to feed the material to the 70 knife by a crank 6 and pitman 7. The crank 6 is connected by means of the bevel gearing with the main drive shaft 8 which is rotated by means of the hand wheel 9, or which may be rotated by a motor in the case 75 of a power machine. The material 4 is fed across the table 5 by means of a plate 10 and ratchet mechanism 11, in a manner well known in the art.

As the slices are cut from the front portion of the material 4 they are received on prongs or spikes 12 which are carried by upright bars 13 secured at their upper and lower ends to the links of chains 14 and 15, respectively. The bars 13 have their upper 80 and lower ends respectively, formed integral with the links of the chains 14 and 15, and are offset relative to the plane of the pivotal connections 16 of the links, as shown in Figs. 4 and 10. The prongs 12 of the bars 13 85 project from the bars toward the plane of the pivotal connections 16 of the chain links, and the prongs are of sufficient length to bring the points slightly past the plane of these pivotal connections, so that when a 90 slice of meat has been forced onto the prongs, the slice will lie substantially in the plane of the pivots. In this way the slice-engaging portions of the prongs are always 95 maintained at a uniform distance from one another, whether the chains 14 and 15 are straight or curved around a bend in their guides. The conveyer chains 14 and 15 are provided respectively, with guide channels 17 and 18 which are held in rigid spaced 100 relation relative to one another by a pair of upright posts 19 and 20. The chain guides 17 and 18 and their connecting posts

19 and 20, together with necessary bracing members, constitute a unitary stacker frame which is pivotally supported on a third post 21 so that it may swing slightly about the post 21 to move the end of the frame, adjacent the knife, a sufficient distance away from the knife to permit cleaning of the parts of the machine. A supporting bracket 22 (Figs. 1 and 3) is provided for the end 10 of the frame adjacent the knife, and the lower end of the post 20 is permitted to extend through an opening 23 in the bracket 22, and a nut 24 is carried by the lower end of the post 20 by means of which the stacker frame may be securely locked in operating position.

The slice carrier, comprising the chains 14 and 15, the upright bars 13 and prongs 12, is caused to travel in its guides 17 and 20 18 by a connection between the carrier and the reciprocating table 5, which connection is best shown in Figs. 9, 10 and 11. A bracket 25 is rigidly secured to the table 5 and carries a pivot 26 on which a lever 27 25 is mounted. A pin 28 is carried by the upper end of the lever 27 and passes through a slot 29 in a bar 30, which is substituted for the upright bar 13 in the end links of the conveyer chains 14 and 15. The lower 30 end of the lever 27 is provided with a roller 31, which travels in a groove 32 in a channel bar 33, rigidly secured to the frame of the machine, as shown in Fig. 1. The channel bar 33 and the groove 32 are given a downward turn, as shown at 34 in Fig. 9 of the drawings, at the end of the bar adjacent the slicing knife. As the table 5 moves to the right in Fig. 9, toward the slicing knife, the lever 27 and the upright bar 30 will be 40 caused to move in unison with the table, since the lever 27 is prevented from rotation about the pivot 26 by the roller 31 which travels in the groove 32. As the table 5 nears the end of its travel, the roller 31 will 45 be prevented from further forward movement by the turn 34 in the groove 32. This will cause the upper end of the lever 27 to travel at a greater rate of speed than the table 5, and thus increase the amount of 50 travel of the slice carrier at the end of the reciprocation of the table. This increase in the travel of the slice carrier occurs after the table has passed the knife and after the slice has been completely severed, and is for 55 the purpose of moving the carrier a sufficient amount to bring the last portion of the slice around the bend at the end of the frame, and into the position on the front side of the carrier, from which it is discharged onto the stack. This will be best 60 understood from Fig. 11 which shows a slice 35 in position to be discharged from the carrier. It will be readily understood that the movement of the bar 30, toward the slicing knife, will push the entire slice car-

rier before it, since the links of the chain are held from buckling relative to one another by their guide channels 17 and 18. A number of idle links are provided immediately adjacent the bar 30, in order that the 70 bars which carry the slices may be forced entirely around the curve at the end of the guide channels adjacent the knife, as shown in Fig. 11. The slice engaging prongs may be omitted from these idle bars, as indicated 75 in the figures of the drawings.

The portions of the guide channels 17 and 18 on the side of the stacker frame, adjacent the slicing machine, may be positioned at a slight angle to the plane of the 80 slices being formed, so that the teeth of the slice carrier are gradually fed into the material as the table 5 and the slice carrying conveyer are moved in unison toward the slicing knife. It should be understood, 85 however, that this feature is not absolutely essential since the slice carrier may be arranged in a plane parallel with the face of the material being sliced and the material will then be simultaneously forced onto 90 all of the prongs by the feeding movement of the table. Where the angular arrangement shown in the drawings is employed, the pin 28 must be made of sufficient length to reach the slot in the bar 30, when the 95 bar is at the end of the guide channel, as shown in Fig. 10.

The guide channels for the slice carrier are so positioned, relative to the slicing knife and the forward edge of the table 5, 100 that the prongs 12 are fed into the material an amount approximately equal to the thickness of the slice prior to disconnection of the slice from the main body of the material, and just sufficient clearance is provided 105 to prevent contact between the points of the prongs and the edge of the knife as the prongs pass the knife. A guard plate 40 is located adjacent the path of movement of the slice as it is carried around the bend at 110 the end of the stacker frame, adjacent the knife. This guard plate, as shown in Fig. 12, deflects the slice away from the knife edge and prevents it from falling away 115 from the points of the prongs 12 at the position where it is thus deflected. The edge of the guard plate farthest from the knife is given a slightly greater curvature than that of the guides for the slice carrier, and a series of grooves 41 are provided in the 120 edge of the guard through which the points of the prongs 12 pass as they travel around the curved end of the guides. By this arrangement, the slice is forced onto the prongs a sufficient amount to permit the points of the prongs to protrude slightly from the outer surface of the slice. This insures the slice against any danger of falling from the prongs while it is being carried to the 125 discharge position.

For discharging the slices from the carrier, a fly 45 is provided which carries a series of arms 46 arranged to pass between the rows of prongs 12 between the uprights 13 and the slice 25 as the slice is carried to the outer side of the stacker, as shown in Fig. 11. The arms 46 are carried by an upright 47 rigidly secured to a shaft 48 journaled in bearings 49 carried on a bracket 50 secured 5 to the frame of the machine by leg screws 51. The shaft 48 also carries a rocker arm 52 to which is pivotally attached one end of an operating bar 53. The opposite end of the bar 53 is bifurcated, as shown in Figs. 4, 15 5 and 6, and extends over a shaft 54 journaled in brackets 55 secured to the under surface of the machine frame. A gear 56 is attached to the shaft 54 and meshes with a pinion 57 carried on the main drive shaft 8. 20 A cam 59 is secured to the shaft 54 having its periphery arranged to engage with a roller 60 carried by a link 61 pivoted at 62 to the bar 53. The link 61 is free to swing about its pivot in one direction, as shown in 25 Fig. 5, but is prevented from movement in the opposite direction by a stop 63 secured to the bar 53. The periphery of the cam 59 normally bears against the roller 60 and the cam is so shaped that when the shaft 54 rotates in the direction of the arrow in Fig. 6, the bar 53 will be forced outwardly during a one-half turn of the shaft and will be held stationary in its outermost position during the second half of the rotation of the shaft. 30 After the shaft has made a complete rotation, the edge of the link 61 will pass over the shoulder 64 on the cam 59 and the bar 53 will be drawn backwardly toward the shaft 54 by a coil spring 65 secured to the bar 53 by means of a pin 66, as shown in Figs. 1 and 4. The operating surface of the cam 59 normally operates against the roller 60 but leaves the roller just before the backward movement of the bar 53 is permitted. The 45 link 61 is provided with an additional bearing surface 67 which extends parallel with the axis of the roller 60, as shown in Fig. 7. The purpose of the additional bearing surface 67 is to release the bar 53 more nearly 50 instantaneously than would be done if a roller alone were used. The bearing surface 67 may be set slightly farther from the cam surface than the periphery of the roller 60, to insure bearing of the cam surface on the roller during the principal portion of the rotation of the cam. In practice, however, it is customary to arrange the surface flush with the roller and permit the more rapid 55 wearing of the fixed surface to provide the necessary relief. The link which carries the roller 60 is pivotally connected to the bar 53 for the purpose of permitting reverse rotation of the shaft 54. When this shaft is rotated in the direction of the arrow in Fig. 60 5, the shoulder 64 of the cam will strike the

bearing surface 67 but this will not prevent rotation of the shaft since the link 61 is free to swing out of the way of the cam, as illustrated in this figure.

When the bar 53 is released by the cam 59 70 and permitted to move toward the shaft 54 under the tension of the spring 65, the fly 45 will be rotated outwardly and downwardly about the shaft 48 and will disengage the slice 35 from the prongs 12 and carry the 75 slice before it into a horizontal position above a receiving table 70. The slice will then fall from the fly onto the upper surface of the table. It should be noted that the fly is operated in the discharging direction by 80 the spring and is returned to its initial position by the cam. This secures uniform speed of operation of the fly during the discharge of the slice independently of the speed of operation of the slicing machine. 85 This arrangement is very important since the range of speed for the best operation of the fly is not very great. Too great a speed will tend to throw the slice away from the machine and so prevent proper stacking, 90 while too slow a speed will permit the slice to drop downwardly in a crumpled condition instead of being carried before the fingers 46 into a horizontal position from which it is dropped upon the stack. Since the 95 spring operates with the same speed, regardless of the speed at which the hand wheel 9 is rotated, the slices are always dropped from the fly under exactly the same conditions, and will therefore fall evenly on top of one 100 another and form a uniform pile. To insure a smoother movement of the fly and to prevent shocks at the limit of its movement, a spring brake or rather a shock absorber 71 (Figs. 1 and 2) is caused to co-operate with a cam 72 carried by the shaft 48. This shock absorber comprises a roller 73 which is constantly pressed outwardly by a coil spring 74 into contact with the periphery of the cam 72. The arrangement is 105 such, that the pressure is very light upon the cam when the fly is in its uppermost position but gradually increases until it becomes sufficient to overcome the decreased tension of the spring when the fly has 110 reached a horizontal or discharging position. In this way the fly is limited in its downward movement and stopped without shock or noise under exactly the same conditions at each operation. It has been 115 found in practice, that as a result of the operation of these parts, the slices may be dropped a considerable distance onto the table 70 and yet will arrange themselves in a uniform stack. This makes it unnecessary to provide a table arranged to move downwardly after each slice is deposited, since the table can be set a sufficient distance below the lower limit of the movement of the fly to permit the formation of 120 125 130

a stack of any height ordinarily desired, without additional adjustment of the position of the table.

The table 70 may be adjustably held in position to receive the slices by means of uprights 75 carried at the ends of horizontal bars 76, projecting forwardly from the frame of the machine. Brackets 77 (see Fig. 13) are attached to each end of the table and are provided with clutch collars 78 which hold the table against downward movement, but permit ready adjustment into any desired position when pins 79 are pressed upwardly by the operator to release the grip of the collars on the bars 75. Coil springs 80 normally hold the clutch collars in gripping position. Handles 81 are secured to the brackets 77 to facilitate adjustment of the table.

The operation of the machine may be summarized as follows: The material to be sliced is clamped upon the plate 10 in the usual manner and the hand wheel rotated to perform a slicing operation. This is all the manipulation required of the operator. As the table 5 is reciprocated back and forth, the prongs 12 on the slice carrier will move in unison therewith for all positions except at the extreme end of the movement of the table toward the slicing knife after the material being sliced is no longer adjacent the prongs. It will thus be seen that the prongs will not interfere with the feeding of the material transversely to the plane of the knife since they always occupy a fixed position relative to the material and reciprocate with it during the time that the material is fed across the table 5. As a particular slice is severed by the slicing knife, it will be carried by the prongs 12 around the curved end of the stacker frame, and will be forced more securely onto the prongs 12 by the guard plate or deflector 40. There will be no distortion of the slice during this operation since the slice engaging portions of the prongs are maintained at a uniform distance from one another, because of their position in the surface of curvature of the conveyer belt. When the slice has been entirely severed, an additional throw is imparted to the carrier by means of the lever 27 and its guide channel 32 and the slice is thus brought into discharge position, as shown in Fig. 11. During the movement of the slice into this position, the fingers 46 of the fly 45 enter the space between the rear of the slice and the bars 13 and just at the time when the table 5 is passing dead center preparatory to its return movement, at which time the slice carrier will also be at rest, the cam 59 releases the spring 65 and the fly is rotated forwardly and downwardly to disengage the slice from the prongs and to discharge it onto the stack.

During the return movement of the table 5

and the slice carrier, the fly is forced upwardly by the first half of the cam 59 so that it is in position to enter between the prongs of the carrier behind the next slice during the next forward movement of the table. The fly is held in this position during the formation of the slice by the second half of the cam 59 which is spaced a uniform distance from the center of the shaft 54. The operation is repeated by a simple continuous rotation of the fly wheel handle until as many slices are deposited upon the table as is desired.

I claim:

1. The combination with a slicing machine having a slicing knife, of a frame and mechanism carried thereby for stacking the slices formed by said knife, said frame and stacking mechanism being movable into and out of operative position adjacent the cutting portion of said knife and means for holding said frame in operative position adjacent said knife during the entire stacking operation.

2. The combination with a slicing machine having a slice cutting knife, of a slice stacker, and means for adjustably supporting said stacker in position adjacent the cutting portion of said knife, said supporting means being arranged to permit movement of said stacker away from said knife to allow for the cleaning of the parts of said machine and to hold said stacker in operative position adjacent said knife during the entire stacking operation.

3. The combination with a slicing machine, of a conveyer for receiving slices formed thereby, a frame for supporting said conveyer, and a pivotal support for said frame arranged to permit movement of said frame away from said slicing machine to allow for cleaning of the parts of said machine and means for holding said frame in fixed position relative to said machine while slices are carried by said conveyer from said machine.

4. The combination with a slicing machine, of a conveyer for receiving slices from said machine, and mechanism for accelerating the speed of said conveyer during a portion of its travel.

5. The combination with a slicing machine, of a movable platform for carrying the material to be sliced, a conveyer for receiving slices as they are formed, and mechanism for moving said conveyer in unison with the movement of said platform during one period of the operation of said machine and at a different rate of movement at another period of said operation.

6. The combination with a slicing machine, of a movable platform for presenting material to the slicing knife, a conveyer for receiving the slices formed by said knife, and mechanism for operating said conveyer in

80

85

95

100

105

110

115

120

125

130

- unison with said platform during the slice forming operation and for imparting a supplementary movement thereto after the slicing operation has been completed.
5. 7. The combination with a slicing machine having a slicing knife, of a platform movable toward said knife for presenting material thereto, a conveyer for receiving the slices formed by said knife, and mechanism for moving said conveyer in unison with said platform during the slicing operation and for imparting a supplementary movement to said conveyer at a greater rate of speed than that of said platform after 10 the slicing operation has been completed for the purpose of transferring the slice received by said conveyer away from the slicing knife.
8. The combination with a slicing machine having a slicing knife, of a conveyer for receiving slices formed by said machine, a movable platform for presenting material to said knife, a movable connection between said platform and said conveyer, and means for causing said connection to hold said platform and conveyer in fixed relation with one another during a portion of the movement of said platform and for causing said connection to impart a movement to said conveyer different from the movement of said platform during another part of the movement of said platform.
9. The combination with a slicing machine, of a slicing knife therefor, a platform movable relative to said knife for presenting material thereto, a conveyer for receiving slices formed by said machine, a lever pivotally connected to said platform and having one end thereof movably connected with said conveyer, and a guiding cam arranged to 35 coöperate with the other end of said lever for holding said lever in fixed position relative to said table during a portion of the movement thereof and for varying the position of said lever relative to said table during another portion of the movement thereof to impart a supplementary movement to said conveyer at a greater rate of speed than the movement of said platform.
10. The combination with a slicing machine, of a conveyer having prongs thereon for receiving slices from said machine, and a device arranged to contact with said slices to force said slices onto said prongs, said device being positioned relative to said conveyer so that a given portion of said conveyer gradually moves nearer to said device as it progresses along the same.
11. The combination with a slicing machine, of a conveyer having prongs thereon for receiving slices from said machine, and a cam shaped guard positioned adjacent the path of movement of said prongs and having portions arranged to enter between said prongs for forcing the slices onto said 65 prongs.
12. The combination with a slicing machine, of a conveyer having prongs thereon for receiving slices from said machine, and a guard for forcing the slices onto said prongs, said guard having grooves therein for receiving the points of said prongs.
13. The combination with a slicing machine, of a conveyer having prongs thereon for receiving slices from said machine, and a guard for forcing the slices onto said prongs and said guard having grooves therein of a gradually increasing depth in the direction in which said prongs move to cause said prongs to penetrate said slices as their points are moved along said grooves.
14. The combination with a slicing machine, of a slicing knife therefor, a flexible conveyer having prongs thereon for receiving slices formed by said knife, a curved guide for said conveyer, and a guard for deflecting slices away from said knife in the direction of movement of said conveyer, the deflecting surface of said conveyer being inclined slightly toward the path of movement of said conveyer to force the 90 slices toward said conveyer, said conveyer having grooves therein arranged to compensate for the inclination of said deflecting surface toward said conveyer to permit free passage of the points of said prongs and to 95 force the slices onto said prongs.
15. The combination with a slicing machine, of a flexible conveyer for receiving slices therefrom, the ends of said conveyer being disconnected from one another.
16. The combination with a slicing machine, of a flexible conveyer for receiving slices therefrom, the ends of said conveyer being disconnected from one another, and means for moving said conveyer in timed relation with the movement of said slicing machine.
17. The combination with a slicing machine, of a flexible conveyer for receiving slices therefrom, said conveyer comprising rigid links pivotally connected with one another and arranged to permit compression force along said conveyer to cause movement thereof.
18. The combination with a slicing machine, of a flexible conveyer for receiving slices therefrom having the ends thereof disconnected from one another, and means for imparting a reciprocatory movement to said conveyer for transferring slices from said machine.
19. The combination with a slicing machine, of a flexible conveyer composed of rigid links pivotally connected with one another for transferring slices away from said machine, a guide for said conveyer, and means for connecting said conveyer at one portion thereof with a movable portion of said machine for operating said conveyer.
20. The combination with a slicing ma- 130

chine, of a flexible conveyer having prongs thereon for receiving slices from said machine, and means for guiding said conveyer toward said machine in a plane at an angle 5 to the direction of movement of the material being sliced.

21. The combination with a slicing machine having a knife thereon for slicing material, a table movable toward said knife 10 for presenting the material thereto, a conveyer for receiving slices formed by said knife, a guide for said conveyer arranged at an angle to the direction of movement of

said material so as to cause the conveyer to gradually approach said material as the 15 material approaches the slicing position, and means for moving said conveyer in unison with said table toward said slicing knife.

In testimony whereof I have signed my 20 name to this specification, on this 5th day of June, A. D. 1917.

EDWARD M. STILES.
